DESIGN.

E. S. JOHNSON.

CHECK AND DEPOSIT SLIP TRAY.

APPLICATION FILED JAN. 16, 1917.

50,788.

Patented May 15, 1917.

*Inventor,
Ernest S. Johnson, by
G. Kennedy.
Attorney.*

UNITED STATES PATENT OFFICE.

ERNEST S. JOHNSON, OF WATERLOO, IOWA.

DESIGN FOR A CHECK AND DEPOSIT-SLIP TRAY.

50,788.

Specification for Design.

Patented May 15, 1917.

Application filed January 16, 1917. Serial No. 142,768. Term of patent 7 years.

To all whom it may concern:

Be it known that I, ERNEST S. JOHNSON, a citizen of the United States of America, and a resident of Waterloo, Blackhawk county, Iowa, have invented a new, original, and ornamental Design for a Check and Deposit-Slip Tray, of which the following is a specification.

Reference is had to the accompanying drawing, forming part thereof.

The figure is a perspective view of a

check and deposit slip tray, showing my new design.

I claim:

The ornamental design for a check and deposit slip tray, as shown.

Signed at Waterloo, Iowa, this 27th day of Dec., 1916.

ERNEST S. JOHNSON.

Witnesses:

PEARL M. STANTON,
WAYNE B. PATTERSON.
